UNITED STATES PATENT OFFICE.

ARMIN KELBER, OF STRASSBURG, GERMANY.

TOY.

1,023,472.

Specification of Letters Patent.

Patented Apr. 16, 1912.

Application filed August 2, 1911. Serial No. 641,915.

To all whom it may concern:

Be it known that I, ARMIN KELBER, a subject of the German Emperor, and residing at Strassburg, Germany, have invented 5 certain new and useful Improvements in Toys, of which the following is a specification.

The present invention has reference to an improvement in toys, and relates more specifically to toy figures with articulated limbs, which in very simple manner are made to assume different, amusing positions relative to one another. Such figures are intended to be used in pairs, facing each other, 15 and have contiguous pairs of arms, provided at the middle with a handle or stud which is grasped between the fingers and then oscillated.

In order to make this invention more readily understood, I will now describe it with reference to the accompanying drawing, in which—

Figure 1 represents a side elevation of two such connected articulated figures, representing boxers, at rest; Fig. 2 shows the same figures in another position; Fig. 3 shows an edge view thereof.

The toy figures *a* and *b*, which may represent human or animal forms, may be made 30 of any suitable material, such as cardboard, wood, metal, or the like. The limbs *c* and *d* are articulated to the bodies proper at *e*, for instance by means of freely operating eyelets or the like. The two bodies are 35 operatively connected by the members *e*, each such member showing one right and one left arm respectively of the facing figures, and I call each such member a pair of arms. The respective pairs of arms are 40 made in one piece, and to the rear of the rear pair, where the hands of boxers clasp, there is secured in suitable manner, for instance by being glued thereto, the handle or stud *f*.

For operating the figures the stud is 45 grasped between thumb and first finger and the figures are stood upon a support *g*, for instance a table-top, so that the feet just touch the support. Upon the fingers now alternately rotating the stud in the one 50 and the other direction, the figures are caused to assume the most various positions relative to each other.

What I claim is:—

1. A toy, comprising two bodies, lower 55 limbs freely movable thereon, a pair of connecting members jointed to said bodies, each such member consisting of one left and one right arm respectively of the facing figures, and a short operating stud rigidly secured 60 to the rear connecting member, substantially as set forth.

2. A toy, comprising two bodies, a pair of contiguous upper limbs and pairs of lower limbs jointed to said bodies, and an 65 operating stud rigidly secured to one of the said contiguous pairs of upper limbs, substantially as set forth.

3. A toy, comprising two bodies, respectively contiguous pairs of arms and independent lower limbs jointed to said bodies, and an operating stud rigidly secured to, 70 and rectangularly extending from, the rear pair of said contiguous limbs, substantially as set forth.

4. A toy, comprising two bodies, contiguous pairs of arms and lower limbs jointed to said bodies, and an operating stud rigidly secured to the middle of, and rectangularly 75 extending from, the rear pair of said contiguous limbs, substantially as set forth.

In testimony whereof I affix my signature in presence of two witnesses.

ARMIN KELBER.
